2,140,000

DISPLAY BOX EASEL COVER

John K. Darragh, Astoria, N. Y., assignor to
 Loose-Wiles Biscuit Company, Long Island
 City, N. Y., a corporation of New York

Application January 14, 1936, Serial No. 59,011

5 Claims. (Cl. 206—44)

The present invention relates to display easels and more particularly to the class of easels used for supporting in display position a cardboard box in such a manner that its contents will be on view.

An object of the invention is to provide such an easel which will support a cardboard box on one end in tilted position with its contents disclosed to view.

Another object is to provide such a display easel which constitutes in another relative position of its parts a box top for the cardboard box which as an easel it is to support in display position.

A further object of the invention is to provide such a display easel in a single piece so formed that from its relatively flat condition as a box top it can, by a simple movement, be transformed into a display easel for supporting the cardboard box on one end in tilted display position with its contents disclosed to view.

Still further objects and advantage of the invention will appear from the following description taken in connection with the accompanying drawing which illustrates, by way of example, a preferred embodiment of the invention and in which—

Figure 1 is a top plan view of the blank from which the display easel is formed;

Figure 2 is a perspective view showing a box and upon it the display easel constituting a cover for the box;

Figure 3 is a perspective view showing the box in display position supported by the easel;

Figure 4 is a perspective view showing the underside of the easel showing its parts in the relative positions they occupy while the easel constitutes a box top;

Figure 5 is a vertical sectional view through the easel in display position; and

Figure 6 is a top plan view of the easel in display position.

Referring in detail to the drawing,—

The blank of Figure 1 has a substantially centrally located box back rest 11 to the left of which, as viewed in Figure 1, is a box supporting section 13, separated from the back rest 11 by fold lines 16 and 17 and intermediate the fold lines a slot 19.

The box supporting section 13 has a portion of its face slotted to form a lock tab 21 which is separated from the adjoining portion of the box supporting section 13 by a fold line 22.

Along opposite side edges of the box supporting section and separated therefrom by fold lines 25

and 26 are side flanges 27 and 28, each of which is provided with a lateral front brace 30 separated from its adjoining side flange by a fold line 31.

Adjoining the box supporting section 13 and separated from it by a fold line 33 is the front easel face 35 which extends from the box supporting sections 13 between the lateral front braces 30.

Separated from the front easel face 35 by a fold line 37 is the inner front face section 38 10 and adjoining the inner front face section 38, separated from it by the fold line 39, is the supporting section locking flange 40.

To the right of the box back rest 11, as viewed in Figure 1, and separated from it by the fold line 43, part of which is slotted as at 44, is the easel back 45 provided with laterally extending easel back braces 47 and 48 separated from it by the fold lines 49 and 50.

Extending from the easel back 45 and separated from it by the fold line 52, part of which is slotted as at 53, is the outer easel bottom section 55.

The partly slotted fold line 58 separates the easel bottom inner section 60 from its adjoining outer section, and the end of the easel bottom 25 inner section is shouldered as at 62 to form the easel locking tab 63 whose ends 65 are adapted to fold inwardly toward each other and down upon the central portion of the tab in order that the tab may be thrust through the slot 19 herein- 30 above referred to.

To form the box top display easel from the blank of Figure 1, viewing the blank as the underside of the easel, the folds are as follows: The locking flange 40 is folded downwardly through 90° along fold line 39. The inner front face section 38 is folded upwardly through 180° along fold line 31. The easel front face 35 is folded upwardly through 90° along fold line 33. The lateral front braces 30 are folded upwardly through 90° along fold line 31. The side flanges 27 and 28 are folded upwardly through 90° along fold lines 25 and 26.

The easel locking tab ends 65 are folded either upwardly or downwardly through 180°. 45 The easel bottom inner section 60 is folded upwardly through 180° along partially slotted fold line 58. The easel bottom outer section 55 is folded upwardly through somewhat more than 90° along fold line 52. The easel back braces 50 47 and 48 are folded upwardly through 90° along fold lines 49 and 50 respectively. The easel back 45 is folded upwardly through nearly 180° along fold line 43. The box back rest 11 is folded downwardly along fold lines 16 and 17 through 55

90°. This brings the easel locking tab 63 opposite the slot 19 through which it is thrust while its ends 65 are folded over after which the ends 65 may be released. This brings the box back rest 11, the easel back 45 and easel bottom into substantially the position of Figure 5.

The lateral front braces 30 and the side flanges 27 and 28 have been folded so that the lateral front braces 30 lie along fold line 33. The inner 10 front face section 38 is folded over these lateral braces toward the box supporting section 13 so that the lateral front braces 30 lie between the easel front face 35 and the inner front face section 38, which brings the fold line 39 adjacent fold 15 line 33 and brings the locking flange 40 along the end face of the box supporting section. The lock tab 21 is pushed up so that the locking flange 40 can contact the end face of the box supporting section 13, whereupon the lock tab can be released, after which it holds all the sections 40, 39, 20 35, 30, 27 and 28 in the folded position of Figures 4 and 5.

The partially slotted fold line 58 permits the easel bottom outer section 55 to be folded down 25 upon the easel bottom inner section 60, as shown in Figure 4, which brings the easel back 45 and the easel bottom outer section 55 into the same plane so that the box back rest 11 can be folded to bring it into alignment with the box supporting section 13. With the parts in this position (Figure 4) the easel back 45 and the easel back braces 47 and 48 lie along and in contact with the box back rest 11, so that the underside of the display easel is now substantially flat and it can be 35 used as the top of the box, as shown in Figure 2.

Folding along fold lines 16 and 17 brings the box top into the position of Figures 3, 5 and 6. Therefore when the display easel used as the top of a box B, as shown in Figure 2, is removed there- 40 from and folded along fold lines 16 and 17 the box B may be placed upon the slanting box supporting section 13 with the box bottom resting against the box back rest 11 and the box interior and contents disclosed to view.

45 It will be noted that the invention provides a single device which is both a box cover and a display easel; the section 13 constitutes a support for one end of the box B; the back rest section 11 is a rest or abutment for the box bottom; and 50 the sloping flanges 27 and 28 not only provide a means for positioning the cover on the box, but also, in the display easel position of the parts, serve to maintain the box support section 13 in box tilting position; the parts fold to form the 55 substantially flat box cover of Figure 2, and from this position, from the display easel by one fold, namely, along lines 16 and 17. The invention may thus be sent out by a manufacturer as a cover for the box containing his goods, and, when 60 received by a retailer, may be used as an easel to display the goods, and, moreover, display them in the box in which they were shipped.

What is claimed is:

1. A display easel box cover having relatively 65 movable parts forming a box cover in one position and a box supporting display easel in another position, and comprising a box support section, means for supporting said section in box tilting display easel position comprising sloping cover 70 positioning flanges on said section, a folding easel section including a back rest, a prop member therefor and a folding bottom associated with said back rest and prop for maintaining them in relatively fixed relation in the easel position 75 of said cover, said back rest and bottom being

foldable into substantial alignment with said box support section, and thereby forming, with said support section and its flanges, a box cover.

2. A display easel box cover having relatively movable parts forming a box cover in one position and a box supporting display easel in another position, and comprising a box support section, sloping cover positioning flanges thereon for supporting said section in box tilting display easel position, a folding easel section including a back 10 rest separated from said box support section by a fold line having a slot, a prop member therefor and a folding bottom having a locking tab in said slot for maintaining said back rest and prop in relatively fixed relation in the easel position of 15 said cover, said back rest and bottom being foldable into substantial alignment with said box support section, and thereby forming, with said support section and its flanges, a box cover.

3. A display easel box cover having relatively 20 movable parts forming a box cover in one position and a box supporting display easel in another position, and comprising a box support section, sloping cover positioning flanges thereon for supporting said section in box tilting display easel- 25 position, a folding easel section including a back rest separated from said box support section by a fold line having a slot, a prop member therefor and a folding bottom comprising a pair of sections foldable upon each other, one of which is 30 provided with a locking tab in said slot for maintaining said back rest and prop in relatively fixed relation in the easel position of said cover, said back rest and bottom being foldable into substantial alignment with said box support section, and 35 thereby forming, with said support section and its flanges, a box cover.

4. A display easel box cover having relatively 40 movable parts forming a box cover in one position and a box supporting display easel in another position, and comprising a box support section, sloping cover positioning flanges thereon for supporting said section in box tilting display easel- 45 position, a folding easel section including a back rest separated from said box support section by a fold line having a slot, a prop member therefor and a folding bottom comprising a pair of sections foldable upon each other, one of which is 50 provided with a locking tab in said slot for maintaining said back rest and prop in relatively fixed relation in the easel position of said cover with said tab in contact with said support section, said back rest and bottom being foldable into substantial alignment with said box support section, and thereby forming, with said support section and its 55 flanges, a box cover with said tab in contact with said back rest.

5. A display easel box cover having relatively 60 movable parts forming a box cover in one position and a box-supporting, display-easel in another position, and comprising a box-support section, means for supporting said section in box-tilting, display-easel position, comprising cover positioning means associated on said section, an easel section including a back rest associated with said 65 support section in folding relation thereto, collapsible means hingedly overlying said back rest for maintaining said back rest in relatively fixed, display-position relation to said box-support section in the display-easel position, said collapsible 70 means and said back rest being foldable into substantial alignment with said box-support section and thereby forming, with said box-support section and cover positioning means, a box cover.
